Attorney

UNITED STATES PATENT OFFICE.

TONY DRENCHKO, OF FRANKLIN, PENNSYLVANIA.

PENCIL-HOLDING ATTACHMENT.

1,294,247.

Specification of Letters Patent. Patented Feb. 11, 1919.

Application filed January 18, 1918. Serial No. 212,496.

To all whom it may concern:

Be it known that I, TONY DRENCHKO, a citizen of the United States, residing at Franklin, in the county of Cambria and State of Pennsylvania, have invented certain new and useful Improvements in Pencil-Holding Attachments, of which the following is a specification.

This invention relates to new and useful improvements in pencil holder attachments, and the primary object of the invention is to provide a new and improved attachment for a pencil holder, which comprises a pen-knife secured thereto and forming an integral part of the same which attachment will greatly increase the efficiency and usefulness of a device of this character, as the knife will always be handy when its use is required.

Another object of this invention is to provide a pencil holder of the conventional type, which is formed of a single piece of metal, having one edge projecting and bent to form a knife holder, and a knife blade pivoted therein, whereby the attachment may be very easily and simply constructed, as the number of parts necessary to form this useful article is reduced to a minimum.

Another object of the invention is to provide a device of this character which is easily and simply constructed, inexpensive to manufacture, and one which will be very efficient in operation.

With these and numerous other objects in view, my invention consists of the novel features of construction, combination, and arrangement of parts which will be herein referred to and more particularly pointed out in the specification and claim.

In the accompanying drawings:

Figure 1 is a perspective of a pencil showing my attachment applied thereto,

Fig. 2 is a longitudinal section through the holder when the same is applied to the pencil, and

Fig. 3 is a sectional view taken on the line 3-3 of Fig. 2.

In describing my invention, I shall refer to the drawings in which similar reference characters designate corresponding parts throughout the several views.

The numeral 1 designates a lead pencil

of the conventional type provided with a suitable eraser 3, and the numeral 2 the holder, which is formed tubular, being constructed of a single piece of metal bent of the desired shape. One edge of the holder designated by the numeral 4 projects from the adjacent edge, and is bent back upon itself in parallel spaced relation to form a knife holder or casing.

Within the holder, formed by the bent edge 4, is positioned a knife blade 5, pivoted as shown at 6 in one end of the holder, said blade being of substantially the same length, and adapted to register within the holder when in normal position, as clearly shown in Fig. 2 of the drawing. The edge of the holder is notched as shown at 7, so as the knife blade may be easily withdrawn from closed position.

To additionally hold the pencil holder on the end of a pencil, an ordinary type of pencil holding clip 9 is positioned on a pencil, as clearly shown in Figs. 1 and 2 of the drawings, and the extremity thereof is adapted for engagement with the inner end of the knife holder. This forms an additional securing means, and may be employed if so desired.

In operation, the holder constructed as has been fully described, is adapted to be positioned on the end of a pencil or the like, and when so arranged, it greatly increases the efficiency of an article of this character, as the knife will always be handy, when it is desired to use the same to sharpen a pencil, or to make an erasure which cannot be ordinarily removed with the rubber eraser commonly positioned in the end of a pencil holder. To sharpen a pencil, the holder is slipped from the end on which it is positioned, but for making the erasure, the knife need only be opened to the position shown in Fig. 1 of the drawing.

From the above description taken in connection with the accompanying drawings, it is thought that a clear and comprehensive understanding of the construction, operation, and advantages of my invention may be had, and while I have shown and described the device as embodying a specific structure, I desire that it be understood that such changes may be made in said structure

as do not depart from the spirit and scope of the invention as claimed.

Having fully described my invention, what I claim as new and desire to secure by 5 Letters Patent, is:

A pencil holder of the class described formed of a single piece of metal bent tubu-

lar, one side edge of said metal projecting and being bent back upon itself in parallel spaced relation, and a knife blade pivoted 10 between the bent portions.

In testimony whereof I affix my signature hereto,

TONY DRENCHKO.
